UNITED STATES PATENT OFFICE.

ALBERT S. POLK, OF ROLAND PARK, MARYLAND, ASSIGNOR TO RENNOUS, KLEINLE & COMPANY, OF BALTIMORE, MARYLAND.

BRUSH-HOLDER.

1,263,925.

Specification of Letters Patent. Patented Apr. 23, 1918.

Application filed April 16, 1917. Serial No. 162,441.

To all whom it may concern:

Be it known that I, ALBERT S. POLK, a citizen of the United States, residing at Roland Park, in the county of Baltimore and State 5 of Maryland, have invented certain new and useful Improvements in Brush-Holders; and I do declare the following to be a full, clear, and exact description of the invention, such as will enable others skilled in the art to 10 which it appertains to make and use the same.

My invention relates to that class of device 15 designed for supporting paint and varnish brushes and the like, whereby the brush may be suspended at a predetermined depth in a receptacle containing paint, varnish or the like, and whereby the brush or brushes may be supported on the exterior of the receptacle if desired, so that they may be easily carried 20 from place to place.

The principal object of the invention is to provide an attachment for paint and varnish cans or buckets which is simple in construction, strong and durable, cheap to 25 manufacture, and effective in operation, the device being capable of application to the various types of brushes used for painting, varnishing, calcimining, and similar work.

Another object of the invention is to provide 30 an attachment for adjustably holding the handles of the brushes so that the latter may be inserted any suitable amount into the paint, varnish, oil or other liquid in the container.

A further object is to provide an attachment 35 which will effectively grip the handle of the brush regardless of the size thereof.

Yet another object is to provide a device by which any brush of the above mentioned 40 classes, or others, can be supported without in any way marring the brush or brush hanger on which it is used.

With the foregoing objects in view, the invention resides in the novel features of 45 construction and unique combinations of parts to be hereinafter fully described and claimed, the descriptive matter being supplemented by the accompanying drawing which constitutes a part of this application 50 and in which:

Figure 1 is a side elevation of the im-

proved holder applied to the upper edge of a paint bucket;

Fig. 2 is a vertical transverse section on the plane of the line 2—2 of Fig. 1; and 55

Fig. 3 is a longitudinal section on the plane indicated by the line 3—3 of Fig. 2.

In the drawing above briefly described, the numeral 1 refers to a cone-shaped coil formed of a single piece of wire, one end of 60 said wire, after forming the larger convolution 2 of the coil, being extended diametrically across said convolution at 3 and anchored at its free end in any suitable manner as indicated at 4, whereby to provide a back- 65 ing member coacting with the adjacent convolution to form a spring clip to receive the upper edge of a paint bucket or the like as shown in Fig. 1.

In the present showing, the end of the 70 wire in question is flattened slightly and is clamped between the large end of the coil and a back plate 5 with which said end contacts, claws 6 being formed on the edge of said plate and clenched around the convolution 75 2 as shown, whereby rigidity is imparted to the aforesaid backing member, said plate also serving as an effective means for displaying advertising matter.

In use, the device is clipped over the edge 80 of a pail or the like as shown in Fig. 1 and the handles of the brushes to be supported are then inserted between the convolutions of the coil 1, the large and more resilient convolutions being capable of springing suf- 85 ficiently to receive the handles of large brushes, whereas those of smaller brushes will be gripped by the smaller and relatively stiff convolutions. The difference in degree of flexibility of the larger and smaller coils 90 is due to the relative size thereof, more metal existing in the larger coils and hence more flexibility or resiliency.

The bucket or other receptacle employed may contain a quantity of linseed oil or other 95 suitable liquid to prevent hardening of the brush bristles, and by sliding the handles of the brushes between the convolutions of the coil, any required amount of said brushes may be inserted in the liquid. The device, 100 however, may in some cases be positioned on the exterior of a paint bucket or the like and

may then be used for supporting the brushes while being carried from place to place.

From the foregoing, taken in connection with the accompanying drawing, it will be obvious that although the improved holder is of extremely simple and inexpensive nature, it will be highly efficient and durable, being self-anchoring, and self-adjusting for different sized brushes.

10 I claim:—

1. A brush holder comprising a conical coil formed of wire with one end of said wire anchored at the larger end of the coil to provide a back member coating with the adjacent convolution to form a spring clip adapted to receive the upper edge of a receptacle.

2. A brush holder comprising a conical coil formed of wire, said wire, after forming the larger convolution of the coil, extending diametrically across said convolution and being anchored to provide a back member

coating with the adjacent convolution to form a spring clip adapted to receive the upper edge of a receptacle.

3. A brush holder comprising a conical coil formed of wire, a circular back plate contacting with the larger convolution of said coil, and claws on the edge of said plate clenched around said convolution.

4. A brush holder comprising a conical coil formed of wire with one end of said wire extended across the larger convolution of the coil, a circular back plate, and claws on the edge of said plate clenched around said convolution, said end of the wire being gripped between said plate and convolution.

In testimony whereof I have hereunto set my hand in the presence of two subscribing witnesses.

ALBERT S. POLK.
